UNITED STATES PATENT OFFICE

116,394

DESIGN FOR AN AMPLIFIER OR THE LIKE

Peter J. Faber, Chicago, Ill., assignor to Montgomery Ward & Co., Incorporated, Chicago, Ill., a corporation of Illinois

Application July 3, 1939, Serial No. 85,827

Term of patent 3½ years

To all whom it may concern:

Be it known that I, Peter J. Faber, a citizen of the United States, residing at Chicago, in the county of Cook and State of Illinois, have invented a new, original, and ornamental Design for an Amplifier or the like, of which the following is a specification, reference being had to the accompanying drawing, forming a part thereof.

In the drawing—

Figure 3 is an end elevational view of the device of Figure 1, illustrating the left-hand end of the device as shown in Figure 1; and

I claim:

The ornamental design for an amplifier or the like, substantially as shown.

PETER J. FABER.
